CLAIM

The ornamental design for an inflatable sports training aid, as shown and described.

DESCRIPTION

FIG. 1 is a perspective view of an inflatable sports training aid showing our new claimed design;

FIG. 2 is a front view thereof, the back view being identical to the front view;

FIG. 3 is a left-side view thereof, the right-side view being identical to the left-side view;

FIG. 4 is a top view thereof; and,

FIG. 5 is a bottom view thereof.

The broken lines depict the portions of the inflatable sports training aid that form no part of the claimed design.

1 Claim, 5 Drawing Sheets
